UNITED STATES PATENT OFFICE.

LAWRENCE FARRAR GJERS AND JOSEPH HUTCHINSON HARRISON, OF
MIDDLESBROUGH, ENGLAND.

APPARATUS FOR REGULATING TEMPERATURE OF HEATED AIR.

SPECIFICATION forming part of Letters Patent No. 630,682, dated August 8, 1899.

Application filed May 2, 1898. Serial No. 679,518. (No model.)

To all whom it may concern:

Be it known that we, LAWRENCE FARRAR GJERS and JOSEPH HUTCHINSON HARRISON, subjects of the Queen of Great Britain and Ireland, residing at Middlesbrough-on-Tees, in the county of York, England, have invented Means or Apparatus for Equalizing the Temperature of Heated Air and other Gases Supplied to Furnaces and other Places, (for which patents have been granted in England, No. 3,605, dated February 14, 1898; in Germany, No. 101,492, dated May 24, 1898; in Belgium, No. 136,065, dated May 23, 1898, and in France, No. 278,144, dated May 21, 1898,) of which the following is a specification.

As is well known, the air-blast of iron-smelting furnaces is usually heated by means of reversible regenerative stoves—such as Cowper's, Whitwells, Ford & Moncur's, and others—which are lined with fire-brick and provided internally with open checker-work of fire-brick arranged so as to leave spaces between and among the bricks, two or more of these stoves being worked alternately in such a way that while one is being heated by the combustion of waste gases from the furnace or by other means another having been heated is used for heating the blast which is passed through it on its way to the furnace. It is obvious that from the time the blast is directed into a freshly-heated stove to the time when it is directed into another stove the temperature of the said blast will gradually decrease, and also that when the blast is again directed into another freshly-heated stove its temperature will suddenly rise, the difference in temperatures often amounting in practice to from about 65° to 150° centigrade, (150° to 300° Fahrenheit.)

It is now generally admitted that blast furnaces work much more irregularly when regenerative stoves of the kind mentioned are used for heating the blast than when the older cast-iron pipe-stoves are used through which air and hot gases are separately passed in a continuous manner and in which the blast is heated to an approximately uniform

degree. Regenerative stoves, however, possess the advantage of being able to heat the air-blast to a much higher temperature than is possible with the older pipe-stove, which results in a reduced fuel consumption in the furnace. When using regenerative stoves, however, the smelting materials in the blast-furnace very frequently form "scaffolds" or ledges of partly-fused material that stick to the sides of the furnace and prevent proper descent of the charge to the hearth or crucible below. Sometimes very great trouble is experienced in removing such scaffolds. In other cases, on account of the melting and withdrawal of the portion of the charge below and the increasing weight of the charge above, the obstruction frequently gives way suddenly, thereby causing a rapid descent of the upper portion of the charge, technically called a "slip," into the hearth below. Meanwhile the proper working of the furnace is not only interfered with, but there is little or no gas formed to supply the steam-generators and stoves used to supply and heat the blast, with the result that the pressure and temperature of the blast decrease at a time when the furnace requires the blast to be at its highest pressure and temperature. With the old form of pipe-stoves, on the contrary, scaffolding and slipping rarely take place. Investigation has shown that the irregularity in the working of blast-furnaces when regenerative stoves are used is due to the variation in the temperature of the blast heated by such stoves. Higher temperature of the blast produces quicker combustion of the fuel, with increased temperature in the vicinity of the tuyers, and a consequently reduced height of melting zone, so that the partly-fused materials in the region slightly above the new melting zone stick together and form a scaffold, which is likely to be a very objectionable one when a very hot stove comes into use after a comparatively cold one.

Now this invention has reference to means or apparatus whereby air or other gas heated by being passed through a regenerative stove or chamber of the kind hereinbefore referred

to previously heated by the combustion therein of gases from a furnace can be maintained at a nearly uniform and high temperature notwithstanding that the temperature of the 5 regenerative stove or chamber through which it is passed and in which it is heated is being gradually reduced. For this purpose there is provided in connection with regenerative stoves or chambers of the kind hereinbefore 10 referred to a heat-equalizer, which is or may advantageously be of similar construction to an ordinary regenerative stove and through which the heated air or gas is passed after leaving each of the regenerative heating- 15 stoves in turn and before it reaches the blast or other furnace or place to which it is to be supplied, the arrangement being such that the excess of heat taken up by the air or gas upon passing through a freshly-heated regen- 20 erative stove will be transferred to and stored in the heat-equalizer to be subsequently given up to cooler air or gas that has passed through the stove after the same has been reduced in temperature, so that the air or gas delivered 25 from the heat-equalizer to the furnace or other place will be at an approximately uniform temperature.

Figure 1 of the accompanying drawings 30 illustrates diagrammatically in sectional plan an arrangement of combined blast-furnace 1, regenerative air-heating stoves 2 ^a ^b, and heat-equalizer 3 according to this invention. Fig. 2 is a cross-section on the line *xx*, Fig. 1.

The heat-equalizer 3 has an inlet 4 in communication with a hot-blast main 5, into which hot air is delivered from each of the regenerative stoves 2 ^a ^b in turn, which are heated by the combustion therein of hot gases from the blast-furnace, as well understood, the connection between each stove and the main 5 being effected through a branch pipe 5^a, controlled by a valve 5^b.

6 is a blowing-engine by which air is delivered through piping 7 alternately to each 45 stove, the connection between each stove and the piping 7 being effected by a branch pipe 7^a with a valve 7^b.

8 is the outlet of the heat-equalizer in constant communication with the horseshoe hot- 50 blast main 9 of the furnace 1.

10 is a gas-main in constant communication, by means of a main 11, with the exit for hot gases from the top of the blast-furnace 1, the said main 10 being adapted to be placed in 55 communication with each of the regenerative stoves 2 ^a ^b by a branch pipe 12, provided with a valve 13.

14 is a main in constant communication with a chimney and also adapted to be placed 60 in communication with each of the regenerative stoves 2 ^a ^b by means of a pipe 15, provided with a valve 16. The arrangement is such that by closing the air-valves 5^b and 7^b and by opening the gas-valves 13 and 16 cor- 65 responding to any regenerative stove hot

gases from the blast-furnace 1 can in a manner well understood be caused to flow through such stoves 2 and by their combustion therein with air heat the same and then pass into the main flue 14 and chimney, after which by 70 closing the gas-valves and opening the air-valves air from the blowing-engine 6 can be caused to pass through the heated regenerative stoves, and thence through the equalizer 3 to the furnace 1.

The heat-equalizer 3 shown is similar in construction to a regenerative stove and comprises an iron shell or casing lined with fire-brick and containing open fire-brick checker-work 3^a. It may consist of a single chamber 80 or it may be divided vertically into two or more sections or chambers. In the drawings it is shown divided into two sections by a division-wall 3^b, such chambers being connected together at the top, so that when the hot air 85 from one of the stoves 2 ^a ^b enters at the inlet 4 it ascends one chamber and descends the other to the outlet 8 and the horseshoe hot-blast main 9, and thence to the furnace 1. When the blast passes from one of the freshly- 90 heated regenerative stoves at its highest temperature into the heat-equalizer 3, the portion of the checker-work in the latter with which it first comes into contact will be at a temperature corresponding approximately to the 95 reduced temperature of the other stove. This blast will consequently give up some of its heat to the heat-equalizer and pass out to the furnace 1 at about a mean between the highest and lowest temperatures given by the 100 stoves. When the temperature of the regenerative stove through which air for the time being is passing and consequently also that of the blast decreases, the heat-equalizer will give up some of its accumulated heat to the 105 blast, which will thus pass out to the furnace with its temperature raised to about a mean between the highest and lowest temperatures given by the stoves. Thus it will be seen that during the first portion of a stove's run 110 the heat-equalizer will absorb heat from the blast and during the latter portion of the run will give up this heat to the blast, after which the blast is directed through another regenerative stove that has in the meantime 115 been heated, and the same process of absorbing and giving up heat repeated.

A further advantage gained by the use of a heat-equalizer according to this invention is that should the furnace work badly from any 120 cause and there is little or no gas given off therefrom to the stoves the stored-up heat in the heat-equalizer will prevent a sudden decrease in the temperature of the blast, which would otherwise occur.

It will be obvious that heat-equalizers such as described can also be used with stoves heated by flame and hot gases from special heating-furnaces instead of by the hot gases from blast-furnaces.

What we claim is—

In a hot-blast-furnace plant, the combination with a blast-furnace, air-heating stoves, and means for causing air and hot gases to flow alternately through each of said stoves, of a heat-equalizer arranged between and in communication with the blast-furnace and stoves and comprising a chamber charged with refractory material arranged and oper-

ating substantially as hereinbefore described to for the purposes set forth.

Signed at 2 Exchange Place, Middlesbrough-on-Tees, England, this 15th day of April, 1898.
